UNITED STATES PATENT OFFICE.

HENRY ALTSHUL, OF NEW YORK, N. Y.

RULING ATTACHMENT FOR TYPE-WRITERS.

No. 818,782.

Specification of Letters Patent.

Patented April 24, 1906.

Application filed March 17, 1903. Serial No. 148,203.

To all whom it may concern:

Be it known that I, HENRY ALTSHUL, a citizen of the United States, residing at the city of New York, borough of Manhattan, in the county and State of New York, have invented certain new and useful Improvements in Ruling Attachments for Type-Writers, of which the following is a full, clear, and exact specification.

10 My invention relates to type-writers; and the same has for its object to provide a simple, efficient, and reliable apparatus which may be readily attached to type-writers for ruling horizontal or vertical lines.

15 Further, the invention has for its object the providing of means whereby the lines may be produced in different colors.

To these ends the invention consists in the novel details of construction and in the combination, connection, and arrangement of parts hereinafter more fully described and then pointed out in the claims.

In the accompanying drawings, forming part of this specification, wherein like letters of reference indicate like parts, Figure 1 is an enlarged detail side view, partly in section, showing the lower end of a bar and a ruling device secured therein constructed according to and embodying my invention. Fig. 2 is a top view thereof, partly in section, taken on the line 2 2 of Fig. 1. Figs. 3 and 4 are enlarged detail side views, partly in section, illustrating modified constructions. Fig. 5 is a perspective view of the ruling device detached from the end of the bar. Fig. 6 is a detail side view of the lower end of a bar and ruling device therein provided with an inking device, and Fig. 7 is a detail end view of the inking device removed from the ruling device.

In said drawings, A designates a bar which is similar in construction to the ordinary type-bars now generally employed in writing-machines and is pivotally supported at its upper end in the frame of the machine and adapted to be operated by means of a key-lever and intermediate mechanism of any of the well-known constructions. The inner or lower end of said bar A, which is free, is preferably made with an enlarged end or head B, which is provided in its upper surface with a rectangular recess or socket C and a circular aperture D, terminating in an enlarged lower end E and forming a socket having a shoulder E' therein.

F denotes a ruling device comprising the

rectangular base G, corresponding in outline with the recess C in the inner lower end of the bar A. From the under side of said base G depends a stem H, which extends through the aperture E and into the socket portion E' of said bar and provided at its lower end with a head I, which is adapted to contact with the shoulder E' of the socket E when the device is raised, and thereby prevent the removal of said ruling device from said bar. Upon the upper surface of said base G is the bearing J, provided with an annular recess K above said base G, and within the bearing J upon a pin L is revolvably mounted a small sharp-edged roller L'.

M denotes a curved leaf-spring which is secured at its inner end by screws M' M' to the upper surface of the bar A, while its forward end which is forked embraces the annular recess K and bears upon the upper surface of the base G in order to hold the entire device locked to its adjusted position within the recessed end of the bar.

N denotes an inking device consisting of a rectangular receptacle or holder P, having openings in its top and bottom sufficiently large to permit of the same being passed over the wheel L' and bearing J and its lower edges adapted to rest upon the shoulders J' J' upon the outer faces of the bearing J above the annular recess K. Within said holder P at its opposite ends are disposed pads Q Q, of felt or other suitable material, which are held in position therein by means of inwardly-projecting prongs a a in the sides of said holder P, the pads Q Q being saturated with the inking or coloring fluid and contact with the edge of roller L and supply sufficient fluid thereto as the same is caused to roll upon the surface of the paper in the carriage.

In the modification illustrated at Fig. 3 the bar A' is recessed in substantially the same manner as the bar A, as shown in Figs. 1 and 2, and carries a ruling device F', also constructed as shown in said Figs. 1 and 2, but instead of being provided with a curved spring M to maintain the ruling device F' in position within its socketed end the depending stem H' is provided with a helical spring O', arranged thereon intermediate the shoulder E' of the socket E' and the head I', which serves the same purpose as the curved spring M, (shown at Fig. 1,) and in the modification illustrated at Fig. 4 the bar A' instead of being provided with a spring to maintain the ruling device F' in position within the socket-

ed end thereof is provided with a screw-threaded aperture at its extreme lower end, within which works a screw *b*, the inner end of which is adapted to contact with the vertical edges of the base *G*³ when said screw *b* is turned to hold the ruling device *F*² locked to its adjusted position within the socketed end of the bar *A*².

The operation of the apparatus is as follows: If it is desired to rule horizontal lines across the sheet of paper in the type-writer, it simply becomes necessary to adjust the roller *L*¹ to a position at right angles to the bar *A* or parallel with the platen by grasping the same between the fingers and raising the same upwardly until the lower edge of the base *G* is clear of the socket or recess *C* in the end of the bar *A* and then turn the same ninety degrees (which will bring the wheel to a position at right angles to the bar *A*) and then release the same, whereupon the spring *M* will at once return the ruling device *F* to its position within the socketed end of the bar and hold the same locked to its adjusted position. Hereupon the key-lever to which the bar *A* is connected is depressed and the roller *L*¹ caused to bear upon the type-ribbon and press the same against the paper on the carriage, and as the carriage is actuated a line will be produced upon the paper therein.

To produce vertical lines upon the sheet, it simply becomes necessary to give the ruling device a quarter-turn and set the same parallel with the bar or at right angles to the platen and then depress the key-lever and rotate the platen in the carriage to the required extent.

When the type-writer does not operate with a ribbon or when it is desired to produce lines of a different color than the ribbons or pads yield, it simply becomes necessary to push the ribbon aside, if the machine has one, and then slip a holder *P*, containing ink or other colored fluid, and operate the same as above described.

It will be observed that by means of my invention I am enabled to produce continuous or broken lines of any desired length either in a vertical or horizontal direction and of any desired color and that I am enabled to produce any number of parallel lines either close together or separated from each other to a greater or less extent, as may be required or desired.

Without limiting myself to the details of invention, which may be varied within the scope of the invention, what I claim, and desire to secure by Letters Patent, is—

1. The combination with a bar, of a ruling device carried thereby comprising a roller and a bearing for said roller, said roller and bearing being supported upon said bar in a vertical position relatively to the longitudinal axis of said bar and adapted for adjustment so as to print either a line parallel with

or at right angles to the printing-line, substantially as specified.

2. The combination with a bar, of a ruling device carried thereby comprising a roller, and a bearing for said roller, said roller and bearing being supported upon said bar in a vertical position relatively to the longitudinal axis of said bar and adapted for adjustment so as to print either a line parallel with or at right angles to the printing-line, and means for securing said bearing to its adjusted positions, substantially as specified.

3. The combination with a bar, of a ruling device carried thereby comprising a roller, and a bearing for said roller carried by said bar and adapted for adjustment to a plurality of positions thereon, and locking means arranged partly on said bearing and partly upon said bar co-operating to hold said bearing to its adjusted positions, substantially as specified.

4. The combination with a bar, of a ruling device carried thereby, comprising a roller, and a bearing for said roller having a base, and adapted for adjustment to a plurality of positions upon said bar, a socket in said bar conforming to and adapted to receive the base on said bearing whereby to hold said bearing to its adjusted positions, substantially as specified.

5. The combination with a bar, of a ruling device carried thereby, comprising a roller, a bearing for said roller having a base thereon, and adapted for adjustment to a plurality of positions upon said bar, a socket in said bar conforming to and adapted to receive the base on said bearing, and spring means for holding said bearing locked to its adjusted positions upon said base, substantially as specified.

6. The combination with a bar, of a ruling device carried thereby comprising a roller and a bearing for said roller, said roller and bearing being supported upon said bar in a vertical position relatively to the longitudinal axis of said bar and adapted for adjustment so as to print either a line parallel with or at right angles to the printing-line, and an inking device for said roller, substantially as specified.

7. The combination with a bar, of a ruling device carried thereby comprising a roller, and a bearing for said roller, said roller and bearing being supported upon said bar in a vertical position relatively to the longitudinal axis of said bar and adapted for adjustment so as to print either a line parallel with or at right angles to the printing-line, an inking device carried by said bearing, and means for securing said bearing to its adjusted positions, substantially as specified.

8. The combination with a bar, of a ruling device carried thereby comprising a roller, and a bearing for said roller carried by said bar and adapted for adjustment to a plural-

ity of positions thereon, an inking device supported upon said bearing, and locking means arranged partly on said bearing and partly upon said bar coöperating to hold said bearing to its adjusted positions, substantially as specified.

9. The combination with a bar, of a ruling device carried thereby, comprising a roller, and a bearing for said roller having a base, 10 and adapted for adjustment to a plurality of positions upon said bar, a socket in said bar conforming to and adapted to receive the base on said bearing whereby to hold said bearing to its adjusted positions, and an inking device supported upon and adjustable with 15 said bearing, substantially as specified.

10. The combination with a bar, of a ruling device carried thereby, comprising a roller, a bearing for said roller having a base thereon, 20 and adapted for adjustment to a plurality of positions upon said bar, a socket in said bar conforming to and adapted to receive the base on said bearing, an inking device supported upon and movable with said bearing, 25 and spring means for holding said bearing locked to its adjusted positions upon said base, substantially as specified.

11. The combination with a bar having an aperture therein, of a ruling device comprising 30 a bearing adapted for adjustment to a plurality of positions, a roller mounted therein, a stem depending from said bearing and extending into the aperture in said bar, and means for holding said bearing to its adjusted 35 positions within said aperture, substantially as specified.

12. The combination with a bar, having a recessed aperture therein, of a ruling device comprising a bearing adapted for adjustment 40 to a plurality of positions, and revolvably disposed within said aperture, a roller mounted in said bearing, and spring means for holding said bearing to its adjusted position within the recessed aperture in the bar, substantially 45 as specified.

13. The combination with a bar, having a socketed recess therein, an aperture extending from said socketed recess, of a ruling device comprising a bearing having a base, a 50 stem depending therefrom and extending into the aperture in said bar, a roller mounted in said bearing, and a spring contacting with the base of said bearing being adapted to hold said ruling device seated within the 55 socketed recess in the bar, substantially as specified.

14. The combination with a bar having a recess, a socket and an aperture connecting said recess and socket, of a ruling device comprising a bearing, a roller mounted therein, a

base corresponding in outline with the recess in said bar, a stem depending from said base and extending through the aperture, provided with a head, an annular recess above said base, and a spring having one end secured to the bar and its other end contacting with said base whereby to hold the same in position within its socket, substantially as specified. 65

15. The combination with a bar having a recess, a socket and an aperture connecting said recess and socket, of a ruling device comprising a bearing, a roller mounted therein, a base corresponding in outline with the recess in said bar, a stem depending from said base 75 and extending through the aperture and provided at its lower end with a head, an annular recess above said base, and a spring having one end secured to the bar, and its other end forked and extending into the annular 80 recess whereby to hold the device in position in the end of the bar, and locked against rotary movement, substantially as specified.

16. The combination with a bar, of a ruling device carried thereby comprising a bearing, 85 a roller mounted therein, supporting means arranged upon the outer surface of said bearing, an inking device comprising a receptacle having an opening at its bottom and adapted to inclose the bearing and be supported upon 90 the supporting means thereon, an opening in the top of said receptacle through which the roller is adapted to extend, pads removably disposed within said receptacle and contacting with the circumference of the roller, and 95 means adapted to engage said pads to hold the same in position within said receptacle, substantially as specified.

17. The combination with a bar, of a ruling device carried thereby comprising a bearing, 100 a roller mounted therein, shoulders upon the outer surface of said bearing, an inking device comprising a rectangular receptacle having an opening at its bottom, and adapted to inclose the bearing and be supported upon 105 the shoulders thereon, an opening at its top through which the roller is adapted to extend, pads removably disposed within said receptacle at its opposite ends and contacting with the circumference of the roller, and inwardly-projecting engaging devices on said receptacle adapted to engage and hold said pads in position therein, substantially as specified. 110
